UNITED STATES PATENT OFFICE

RENÉ ARCQ, OF BRUSSELS, BELGIUM

APPARATUS FOR DRAWING SHEET GLASS

Application filed December 26, 1930, Serial No. 504,877, and in Belgium December 26, 1929.

This invention relates to the apparatus for drawing sheet glass of the kind used in the Fourcault process, in which the drawing takes place vertically during the ascending movement of the sheet of glass.

5 The object of the invention is to avoid, in apparatus of this kind, the disadvantages which result frequently from a loosening of the edges of the sheet; these edges, when not maintained, get sometimes accidentally loose in the inside of the machine, slide along the annealing casing and break themselves on the float or drawing apparatus properly so called.

10 This results in a loss in the production and also a damage to the edges of the float from which the sheet emerges which causes defects in the sheets and a decrease in the quality of the products.

15 With this object in view my invention essentially consists in the special arrangement and combinations of parts, as will be herein-after fully described and pointed out in the appended claims.

20 Referring to the annexed drawings:

25 Figure 1 is a front view showing diagrammatically, partly in section, the whole arrangement of the pairs of driving rolls acting on the drawing sheet and the cooperation between these driving rolls, of the apparatus forming the subject matter of the invention, this apparatus being shown in side elevation.

30 Figure 2 is a view showing partly in section along line II—II in Figure 1 and partly in a side elevation, when seen from the inside of the annealing casing of the machine.

35 Figure 3 is a horizontal section taken through line III—III in Figure 2.

40 Figure 4 is an elevation view of the apparatus, seen from the outside of the annealing casing.

45 Referring to the drawings, 1 shows in section one of the side walls of the annealing casing of an apparatus for drawing sheet glass and 2 the driving rollers, which are arranged by pairs and serve to carry away the sheet glass 3.

50 These rollers 2 are mounted in the usual manner in bearings (not shown) which are

supported by the walls of the annealing casing 1 and are put into rotation by suitable means so as to cause the drawing of the sheet of glass 3 vertically from the place where it leaves the usual float or drawing machine properly so called. 55

As it is well known, the rollers 2 which are arranged by superposed pairs, do not draw the sheet of glass 3 on its whole width, the edge 4 (Figure 3) of this sheet having a thickness slightly larger than that of the body of the sheet, so that it is necessary to provide at the ends of the rollers 2, a part 5 of a diameter slightly smaller than that of the rollers 2. As a result, the edges 4 of the sheet of glass are not maintained and, when they get accidentally loose, slide along the annealing casing, and may get broken on the float or drawing machine, causing thus the fall of the sheet. 65

70 According to the present invention, in order to avoid this inconvenience, it is made use, between the superposed pairs of rollers 2, or at least above the lower pair, of a device adapted to maintain the edges 4 of the sheet and to prevent their falling down. This device comprises two small auxiliary rollers 6 preferably covered with asbestos, leaning against the edge 4 of the sheet of glass 3. 75

75 In the example shown these rollers 6 are keyed on small shafts 7 rotating freely in the arms 8 connected with rods 9 mounted in bearings 10, supported by a cast-iron plate 11, fixed by any suitable means, for instance by means of bolts 12, to the annealing casing 1, so as to cover an opening 13, provided in that place in the annealing casing. These rollers 6, the supporting arms 8 of which, form between themselves an angle which is open at its lower part, lean against the edge 4 of the sheet of glass, and may rotate freely with their shafts 7 in the arms 8, in the direction of the upward motion of the sheet of glass 3, that is to say, in the direction indicated by the arrow 14 on Figure 2; their rotation in the opposite direction is prevented by a ratchet-wheel 15 carried by one of the shafts 7 and in which engages a pawl 16, mounted at the extremity of one of the arms 8 bearing the shaft 7. In order to allow these 90

rollers 6 to be drawn apart when necessary, the rods 9 carrying the arms 8, are provided outside of the cast-iron plate 11 with handles 17 allowing the rotation of the rollers 6 together with the supporting arms 8 around the rods 9.

The plate 11 is provided above the rollers 6, with a man-hole 18 normally closed by a door 19 which can slide on a rod 20.

10. The plane of tangency which is common to the drawing rollers 2 of the sheet 3 and to the rollers 6, acting on the edges of the sheet, is vertical and passes through the slit of the float or drawing machine properly so called (not shown).

11. As shown in Figure 3, the rollers 6 are somewhat conical in shape, their largest diameter being adjacent to the lateral wall of the annealing casing 1 of the machine, so as to prevent that an edge 4, detached from the sheet of glass above the rollers could slide between the latter, the space at that point, being smaller than the thickness of the edge of the ascending sheet.

12. The described device works in the following manner:

13. When the machine is normally working, the sheet of glass 3 drawn by the pairs of rollers 2, passes between the rollers 6, leaning simply against the edge, and rotating in the direction in the ascending sheet. If, accidentally, an edge 4 of the sheet gets loose between two pairs of rollers 2, this edge is maintained by the rollers 6, which are prevented from rotating in the opposite direction by the pawl 16, and as a result the action of the lower pairs of rollers 2, is rendered easier as regards the carrying with the sheet of glass. If the broken edge, coming from the top of the machine, falls on the rollers 6, this edge cannot slide between these rollers because of their conical shape; moreover, these rollers being of a smaller diameter relatively to the large diameter of the drawing rollers 2, the pieces of glass falling on these rollers 6, are thrown automatically away in the hollow parts of the machine.

14. The rollers 6 are preferably made of asbestos, in order to secure that the contact with the glass should produce in the sheet neither stains, nor adherences.

15. Experience has shown that such a device, not only decreases considerably the breakage, but further prolongs the life of the float or drawing machine properly so called and enables to increase the production as well as to improve the quality of the manufactured products, while making the workmen's labour easier and reducing the number of workmen.

16. What I claim is:

17. In an apparatus for drawing sheet glass in combination with the successive pairs of drawing rollers and with the annealing casing of the apparatus, pairs of auxiliary roll-

ers arranged between the superposed pairs of drawing rollers, and bearing freely against the edge of the sheet of glass and means whereby the said auxiliary rollers are prevented to rotate in the direction opposite to the direction of drawing of the sheet.

18. In an apparatus for drawing sheet glass, in combination with the successive pairs of usual drawing rollers extending parallelly on both sides of the sheet of glass and with the annealing casing of the apparatus, pairs of auxiliary conical rotatable rollers arranged between the superposed pairs of drawing rollers and bearing freely against the thickened edge of the sheet of glass and means whereby the said auxiliary rollers are prevented to rotate in a direction opposite to the direction of drawing of the sheet.

19. In an apparatus for drawing sheet glass, in combination with the successive pairs of usual drawing rollers extending parallelly on both sides of the sheet of glass and acting on the major portion of the width of the sheet and with the annealing casing containing the said pairs of rollers, pairs of auxiliary conical and rotatable rollers arranged between the superposed pairs of drawing rollers and bearing freely against the edge of the sheet of glass on that part of the edge which is not maintained by the pairs of drawing rollers, and means whereby the said auxiliary rollers are prevented to rotate in a direction opposite to the direction of drawing of the sheet of glass.

20. In an apparatus for drawing sheet glass, in combination with the usual pairs of drawing rollers extending parallelly on both sides of the sheet of glass and acting on the major portion of the width of the sheet, and with the annealing casing, pairs of auxiliary conical and rotatable rollers, arms carrying the said auxiliary rollers, the said arms forming a downwardly open angle between themselves for each pair of auxiliary rollers, means whereby the said auxiliary rollers can be displaced apart and means whereby they are prevented to rotate in a direction opposite to the direction of drawing of the sheet of glass.

21. In testimony whereof I have affixed my signature.

RENE ARCO.
